PORTABLE RADIOPHGRAPHIC EXPOSURE UNIT
Caleb P. Moore, Utica, Mich., assignor to General Motors Corporation, Detroit, Mich., a corporation of Delaware
Filed Mar. 29, 1961, Ser. No. 96,932
3 Claims. (Cl. 250—105)

This invention relates to a radiographic exposure unit, and more particularly to a portable radiographic exposure unit utilizing radioisotopes as the source of radiation.

Recent developments in low radiation energy radioisotope source materials have made it possible to use such sources in both medical and industrial radiography. It is well known to use high energy radioisotope sources such as cobalt-60 for industrial radiography. Such high energy sources have been limited to applications permitting use of bulky shielding, and hence, have been limited to more or less stationary installations. The advent of the low energy sources has led to foreseeable uses of portable radiographic units whereby doctors in remote areas or field hospitals and veterinarians on farms could readily take X-rays of their patients since neither complex electrical power supplies nor bulky X-ray equipment would be required. Similarly, in industry, radiography could be made available where either space or cost considerations make conventional X-ray or high energy radioisotope radiography impractical.

Accordingly, it is an object of this invention to provide a lightweight, compact, and relatively inexpensive radiographic exposure unit.

This invention is carried out by providing a body member containing shielding material and a movable radioisotope source surrounded in part by shielding material whereby the source may, by simple translational movement, be located so that it is completely shielded or partially unshielded to provide a source of radiation.

The above and other advantages will be made more apparent from the following specification taken in conjunction with the accompanying drawings in which like numerals refer to like parts, and in which:

FIGURE 1 is an elevational cross section view of an exposure unit in open position according to the invention;

FIGURE 2 is an enlarged view of the radiation window of FIGURE 1;

FIGURE 3 is an elevational cross section view of an exposure unit of FIGURE 1 in closed position; and

FIGURE 4 is an elevational cross section end view along line 4—4 of the exposure unit of FIGURE 1.

The requirements of a portable exposure unit containing radioisotopes is manifold. In order to be portable, it must be both lightweight and compact. To be practical, it must also serve as the storage container for a radioactive source and also must meet the rigid standards applying to containers for the transportation of radioactive materials. Hence, such an exposure unit needs to be of very durable construction and provide good radiation shielding even when accidentally exposed to high temperatures such as encountered in a burning building. It will be seen by reference to the following description that the present invention meets all of these requirements.

Suitable low energy gamma ray sources include the rare earth metals. For example, samarium-153, thulium-170, lutetium-177, ytterbium-169, or gadolinium-153 may be used in the form of the metal, the enriched metal, or the rare earth oxide powder mixed with aluminum and sintered to form a cermet. The cermet type of sources and the method of fabricating the same are more fully described in the patent application of Black et al., S.N. 19,009, filed March 31, 1960, and assigned to the assignee

2

of the present invention. These sources are encased in an aluminum or stainless steel source container.

Referring now to FIGURES 1 through 4, the exposure unit includes a housing or body 10 having an elongated U-shaped lower portion 12 with an upwardly extending flange 14 along either side and a generally flat cap portion 16 having depending flanges 18 along either side mating with the flanges of the U-shaped lower portion 12. Both portions 12 and 16 of the body are preferably made of stainless steel and are fastened together by steel pins 20. The bottom of the body 10 has a cylindrical insert 22 of radiation shielding material. This material could be lead. However, it is preferably that a more durable substance, such as a tungsten composition, be used. Such a composition is known commercially as Mallory 1000 metal, which contains 90% tungsten, 6% nickel, and 4% copper. This material has a minimum density of 16.7 grams per cubic centimeter, has a very high tensile strength, and will retain its integrity for temperatures up to 2300° F. The bottom of the body 10 also has longitudinally spaced from the insert 22 an aperture 24 of truncated conical form flaring outwardly toward the lower surface of the body 10. A support leg 26 is secured at each bottom corner of the body and a convenient carrying handle 28 is secured to the cap portion 16. The cap portion 16 has a slot 30 located beneath the handle 28 and access holes 32 through the handle 28 communicate with the slot 30. An apertured lug 34 extends from the left end of the cap 16.

30 A shutter or slide member 36 preferably of stainless steel fits within the opening of the U-shaped body for translational movement therein. A cylindrical cavity 38 in the righthand portion of the slide member 36 contains a block 40 of radiation shielding material secured by pins 41 which block in turn has a central aperture 42 adapted to support a container 44 for radioactive material 46. The radioactive material 46 is situated in a nose portion of the container which extends downwardly in the aperture 42 and protrudes into a conical portion 48 of the aperture 42 which flares outwardly toward the bottom of the slide member 36. The lower part of the flared aperture 48 is closed off by a thin diaphragm 50 of stainless steel. The diaphragm 50 is held in place by a retaining ring 52 which is staked into place. The upper end of the aperture 48 in the shielding block 40 is threaded to receive a threaded cap 54 which is also made of radiation shielding material. A thin gasket 56 of soft metal between the shielding block 40 and cap 54 provides a tight seal and, in conjunction with the stainless steel diaphragm 50 in the flared aperture 48, seals the source container 44 into the shielding block 40. This construction, hence, will be effective to prevent any loss of radioactive material 46 in the event the source container 44 becomes damaged due to exposure to very high temperatures. However, since the stainless steel diaphragm 50 is very thin, preferably about .003 inch thick, it does not act as an effective radiation shield, but rather serves as a window.

60 A threaded pin 58 extending from the top of the slide member 36 rides in the slot 30 provided in the cap 16 thereby limiting the extent of movement of the slide 36 within the body 10. In order to disassemble the exposure unit for periodic replacement of the source material, it is necessary merely to move the threaded pin 58 into alignment with the openings 32 of the carrying handle 28 so that the pin 58 may be removed by a screwdriver. Then the slide 36 may be completely removed from the body 10. A handle 60 at the left end of the slide member 36 has an aperture 62 therethrough which, when the slide 36 is in its closed position as shown in FIGURE 3, is immediately below the aperture 64 of the lug 34 of the cap portion 16. Hence, a lock or other fastening

means (not shown) may be inserted through the apertures 1, 64 to prevent inadvertent or unauthorized opening of the unit. When the slide 36 is thus locked in this position, the threaded pin 58 will be beneath the handle 28 in alignment with the openings 32 so that the pin 58 cannot be removed by unauthorized personnel.

Obviously, the unit may be used in the horizontal position shown in the drawings or may be tilted vertically or otherwise. In order to hold the slide member 36 in either open or closed position, regardless of the orientation of the unit, two spring biased ball detents 66 are provided in the lower part of the body 10 and mate with either pair of indentations 68 on the left portion of the bottom of the slide or a pair of indentations 70 near the center of the slide 36. A boss 72 is provided around the outer opening 24 so that a diaphragm (not shown) may readily be mounted over the opening to modify the cone angle of emitted radiation, or so that larger cone extensions can be employed when desired.

In operation, the unit is placed the desired distance from the subject to be X-rayed with the axis of the conical aperture 24 aligned with the subject. Then the shutter or slide 36 is manually moved to the open position (FIG. 2) for the desired period of exposure time and is then moved back to the closed position (FIG. 3). While the slide is in open position, the operator of the unit as well as all other persons not in line with the aperture 24 are shielded from the radiation by the shielding block 40 and cap 54 carried by the slide member 36. When the slide 36 is in closed position, the cylindrical insert 40 of shielding material in the body of the unit blocks the radiation coming through the stainless steel window 50 of the shielding block 40, thereby providing effective shielding to minimize radiation fields to suitable intensity for safe storage or transportation. For example, where the shields comprise the tungsten alloy and the insert shield is 2" dia. by $1\frac{1}{16}$ ", the shielding block is $2\frac{3}{4}$ " dia. by $1\frac{1}{16}$ ", and the shielding cap is 2" dia. by $1\frac{15}{16}$ ", 60 curies of any radioactive material and larger amounts of some materials may be safely shielded.

It should be noted that although the preferred embodiment shown herein is limited to the use of one source of radioactive material 46 within the exposure unit, the design can easily be extended within the scope of the invention to provide for the use of two or more sources so that the operator can selectively operate the shutter 36 to expose the desired source.

Thus it will be readily seen that the invention provides a compact and lightweight radiographic unit which is simple in operation and does not in any way sacrifice adequate shielding or rugged construction for portability.

It is understood that the preferred embodiment of the invention described herein is not intended to limit the scope of the invention which is defined by the following claims.

I claim:

1. A portable radiographic exposure unit comprising a body, a hollow channel portion defined by and extending through said body proximate one side thereof, the other side of said body being provided with a first mass of radiation shielding material on one end thereof and a first conical aperture on the other end thereof, a rectilinearly movable slide member within said channel, a radiation source mounted in a cavity in said slide member, means for limiting escape of radiation from said source to one direction comprising a second mass of radiation shielding material on said slide member enveloping said source and defining a single conical aperture herethrough, said source and the second said aperture

being arranged to register with said first mass of radiation shielding material when said slide member is positioned at one extreme position of its stroke and to register with said first conical aperture when said slide member is positioned at the other extreme position.

5. 2. A portable radiographic exposure unit comprising a body provided with a carrying handle, a hollow channel portion defined by a U-shaped body portion having a cap portion thereon, said channel portion extending 10 through said body proximate one side thereof, the other side of said body being provided with a first mass of radiation shielding material on one end thereof and a first conical aperture on the other end thereof, a rectilinearly movable slide member within said channel, a radiation 15 source mounted in a cavity in said slide member, means for limiting escape of radiation from said source to one direction comprising a second mass of radiation shielding material on said slide member enveloping said source and defining a single conical aperture therethrough, said source 20 and the second said aperture being arranged to register with said first mass of radiation shielding material when said slide member is positioned at one extreme position of its stroke and to register with said first conical aperture when said slide member is positioned at the other extreme 25 position, a handle connected to said slide member for rectilinearly moving said slide member relatively to said body, and detent means for indexing said slide member at each of its extreme positions.

3. A portable radiographic exposure unit comprising a box-shaped body provided with a carrying handle, a hollow channel portion defined by a U-shaped body portion having a cap portion thereon, said channel portion extending through said body proximate one side thereof, the other side of said body being provided with a cylindrical mass of radiation shielding material on one end thereof and a first conical aperture on the other end thereof, a rectilinearly movable slide member within said channel, a radiation source mounted in a cavity in said slide member, means for limiting escape of radiation from 30 said source to one direction comprising a second mass of radiation shielding material on said slide member enveloping said source and defining a single conical aperture therethrough, a diaphragm of radiation permeable material closing the second said conical aperture, said source and the second said aperture being arranged to register with said cylindrical mass of radiation shielding material when said slide member is positioned at one extreme position of its stroke and to register with said first conical aperture when said slide member is positioned at the other extreme 35 position, a handle connected to said slide member for rectilinearly moving said slide member relatively to said body, a ball detent means for indexing said slide member at each of its extreme positions, and abutment means on both said body and said slide member for limiting the 40 stroke of said slide member in relation to said body so as to prevent said slide member from becoming separated from said body.
